UNITED STATES PATENT OFFICE.

MARIUS H. HANSEN, OF CHICAGO, ILLINOIS.

DESIGN FOR A RIM FOR SCALE-DIALS.

42,359.

Specification for Design.

Patented Mar. 26, 1912.

Application filed December 27, 1910. Serial No. 599,535. Term of patent 14 years.

To all whom it may concern:

Be it known that I, MARIUS H. HANSEN, a citizen of the United States, residing at Chicago, in the county of Cook and State of Illinois, have invented a new, original, and ornamental Design for a Rim for Scale-Dials, of which the following is a specification, reference being had to the accompanying drawing, forming a part thereof.

The figure is a face view of a scale dial

provided with a rim showing my new design.

I claim:

The ornamental design for a rim for scale dials as shown.

MARIUS H. HANSEN.
